SIGNAL DEVICE

Charles F. Wallace, Westfield, N. J., assignor to
 Wallace & Tierman Products, Inc., Belleville,
 N. J., a corporation of New Jersey

Application July 30, 1928, Serial No. 296,280

8 Claims. (Cl. 177—329)

This invention relates to signal devices or apparatus. The invention has been made especially with the idea of providing an improved self-contained electrically operated flashing lantern for use as a land or marine traffic warning or other signal light, although flashing light apparatus according to the invention may be used for other purposes.

The invention aims especially to provide an improved flashing lantern which is not affected by exposure to dampness, rain or other water, or dust; and which is self-contained, compact, and of relatively light weight so as to be, if desired, readily portable by hand. To these ends, the invention consists in the combinations, constructions and arrangements of parts hereinafter described and claimed.

A full understanding of the invention can best be given by a detailed description of a portable flashing lantern embodying the various features of the invention in an approved form, and such a description will now be given in connection with the accompanying drawings showing such an approved construction, in which:

Fig. 1 is a sectional view of the apparatus, the automatic controlling mechanism being shown in end elevation looking from the left of Fig. 2;

Fig. 1a is a detail side view of one of fastening means for securing the cover of the battery casing to the body of the casing;

Fig. 2 is a side elevation of the controlling mechanism looking from the right of Fig. 1;

Fig. 3 is a sectional view of the controlling mechanism looking in the same direction as Fig. 2;

Fig. 4 is a sectional view taken on line 4—4 of Fig. 2;

Fig. 5 is a detail view taken on the line 5—5 of Fig. 2;

Fig. 6 is a sectional view taken on line 6—6 of Fig. 1, looking upward;

Fig. 7 is a sectional view taken on line 6—6 of Fig. 1, looking downward, the terminal nuts being removed; and

Fig. 8 is a sectional plan view of the battery container with the battery cells removed, showing the bottom of the container.

In the apparatus shown, the signal device proper is an incandescent electric light, or lamp A, which is mounted at the central or focal point of a Fresnel lens B and which receives current through a circuit controlled by a circuit-controlling mechanism C, the current being supplied from a dry cell battery D which is conveniently contained

in a casing or container E on which the lens is mounted.

The battery casing E in the particular construction shown is a vertical, cylindrical container having a body portion 10 open at the top, and a flanged cover 11 adapted to tightly close the open top of the body 10. The lens B is mounted on the cover and held clamped between the cover and a cap 12. The cap 12 is secured and drawn downward toward the cover by means of tension rods 15, and when the device, or lantern, is intended for portable use, it is conveniently provided with bail handle 16 the ends of which are secured by the upper ends of the tie rods 15.

Removably secured to the under side of the cover 11 so as to be housed within the battery casing when the cover is positioned on the casing body 10, is a closed container 20 within which is mounted the circuit-controlling mechanism C and from the upper wall of which a hollow lamp-20 supporting post 21 extends upward, the post 21 passing through an opening 22 in the cover 11 when the casing 20 is secured in position against the under side of the cover. The post 21 has at its upper end a lamp socket 23, and is of such height and so positioned laterally with respect to the lens B that the filament of the lamp A set in the socket 23 is located at, or approximately at, the focal point of the lens. The lens will usually be located centrally of the cover 11 and the opening through which the lamp post 21 extends will then be at the center of the cover 11.

The dry cell battery D, by which current is supplied to the lamp, consists, as shown, of four dry cells positioned within the casing E, resting on a plate 25 which is supported by lugs 26 a little above the bottom of the container, so that if, through any possibility, a slight amount of water should gain entrance into the container, the bottoms of the battery cells would not stand in contact therewith.

The battery cells, as shown, are connected in series by means of a connecting card consisting of a sheet 27 of insulating material having connecting strips 28a, 28b and 28c of conducting material secured thereto by eyelets 29 so located on the card that when the batteries are set in position the card may be positioned on top of the cells with the binding posts which project from the top of the cells extending through the eyelets so that the strips 28 will connect the positive terminal of one cell with the negative terminal of the adjacent cell. The card 27 is secured in position and good contact with the cell terminals 50 55 55

assured by means of the usual terminal nuts 30. The terminal nuts are omitted from Fig. 7.

From the positive terminal 31 of the battery cell at one end of the series a connecting strip 5 32 extends inward to a centrally located contact button 33, and similarly a connecting strip 34 extends from the negative terminal of the cell at the other end of the series and carries a contact button 35. The connecting strips 32 10 and 34 are flat spring strips tensioned to tend to move their free ends upward away from the card 27. In order to provide a switch for opening and closing the battery circuit as desired, the connecting strip 28c between the positive 15 terminal of one of the cells and the negative terminal of the adjacent cell is connected only to one of said terminals so as to serve as a pivoted switch, the other battery terminal being provided with a short contact piece 36 the end 20 of which is turned slightly upward so as to permit the switch 28c when turned to contact closing position to slip in beneath it.

The circuit-controlling mechanism C mounted within the closed container 20 comprises a 25 periodic oscillating member and means for maintaining the oscillations of such member, the oscillating member in the construction shown being a spring balance wheel 40 the oscillations of which are maintained by a spring-driven train 30 acting through an escapement lever 41. The lamp circuit extends from a contact terminal 42 fixed in the bottom of the container 20 in position to make contact with the terminal button 33, when the parts are assembled, by wire 35 43 to binding post 44, and thence by a wire 45 to the bottom terminal 94 of the lamp socket 23. From the side of the lamp socket, a wire 46 makes connection to a fixed contact 47 with which a movable contact 48 cooperates to open 40 and close the lamp circuit. The movable contact 48 is grounded to the wall of the casing 20 through which connection is made to the battery 45 through the terminal button 35, which, when the parts are assembled, is in contact with the bottom wall of the container.

The balance wheel 40 and the driving train therefor are mounted in a frame comprising side plates 50 and 51 and spacing posts 52, and the frame is secured to a bracket 53 which has one 50 end secured to the bottom of the container 20 and extends upward to the top of the container, having a horizontal extension 54 which carries the lamp post 21. The fixed contact 47 is secured to a flat bar 55 of insulating material, and the movable contact 48 is carried by a contact arm 56 which extends from a shaft or spindle 57 mounted in the side plates 50 and 51. A spring 58 tends to move the contact arm 56 to carry the contact 48 away from the fixed contact 47 60 to open the lamp circuit. The end of the arm 56 extends through a notch or opening in the plate 55 the edge of which serves as an abutment to limit the circuit opening movement of the arm.

An actuating arm 60 extends from the movable contact arm 56, or from the spindle 57, into the path of an abutment on the balance wheel 40, the arm 60 being positioned so that, as the 65 balance wheel approaches the end of its oscillation in one direction, the abutment will strike and move the arm 60 to cause the movable contact 48 to move into engagement with the fixed contact 47. The escapement lever pin 61 conveniently serves as the arm-actuating abutment 70

on the balance wheel. The actuating arm 60 is most desirably a spring arm, so as to avoid excessive jarring of the balance wheel and so as to give the desired period of closure of the lamp circuit. By varying the stiffness of the spring arm, the duration of the period of closure of the circuit may be varied as desired, the period being shorter as the spring is stiffer. The lamp circuit will thus be closed and the lamp lighted intermittently at the end of each oscillation in 10 one direction of the balance wheel 40. The timing of the succession of flashes will be determined by the period of the balance wheel.

This make-and-break device for controlling the lamp circuit has the advantage that the force 15 under which the movable contact moves against the fixed contact is relatively large, while the power consumed in operating the movable contact is relatively very small since the energy required to operate the arm 60 to move the contact 48 and hold it in engagement with the contact 47 is to a large extent returned to the balance wheel as the latter begins its return movement after having been stopped by the resistance of the arm 60. Furthermore, the device has the advantage 25 that, even though the power of the driving train may through any possibility become so relatively weak as to result in the arc of swing of the balance wheel becoming shorter and the interval between circuit closings and flashings of the lamp 30 becoming longer, yet the duration of contact and length of the resulting flashes are not varied by variation of the arc of swing, but remain constant.

The driving train of the circuit-controlling 35 mechanism is driven by driving means to which energy is restored at intervals by automatically acting electro-magnetic means which is, most desirably, supplied with current from the same battery which supplies the lamp. As shown in 40 the drawings, the train is driven by a spring 65 which is tensioned at intervals by the action of an electro-magnet 66. The magnet 66 is mounted on the plate 51 and has an armature 67 pivoted on a pin 68 so as to extend adjacent to the pole 45 70 of the magnet and to be movable toward and away from the pole.

The driving spring 65 is formed from a piece of 50 spring wire which is coiled about the pivot pin 68 and has its free end hooked under one of two short arms 71 extending from the free end of the armature 67. The other end of the wire, extending from the coil about the pivot pin 68, is secured so as to hold the spring under suitable tension. The spring will thus tend to move the armature 55 away from the magnet pole, and when the armature is drawn toward the pole the tension of the spring is restored.

A spring arm 72, formed by a piece of spring 60 wire coiled about a pin extending between the armature arms 71, extends downward and has a bent-over end 73 which serves as a pawl to cooperate with a ratchet wheel 74 on the main driving arbor of the train. The other end of this wire 65 beyond the coil engages beneath the end of the armature to hold the spring arm 72 under tension so that its bent-over end, or pawl, 73 is yieldingly held against the edge of the ratchet wheel 74. As the armature moves upward under tension of the driving spring 65, therefore, the pawl 73 will move upward and turn the ratchet wheel 74; and when the armature is attracted by the magnet to restore the energy of the driving spring, the pawl 75

will be moved downward to engage a lower notch of the ratchet wheel.

The magnet circuit is controlled and closed at intervals by a make-and-break device actuated by the movement of the armature 67. This device comprises a fixed contact 75 carried by a rigid bracket 76 extending downward from a plate 77 of insulating material at the upper end of the magnet coil, and a movable contact 78 carried by a pivoted arm, or lever, 79, which extends upward from its pivotal connection to a bracket 80 secured to a plate 81 of insulating material at the lower end of the magnet coil. An actuating arm 85, extending downward from the pivoted end of the armature 67, extends into an opening 86 in a lug on the contact arm 79, the opening 86 being somewhat wider than the thickness of the arm 85 so as to provide for lost motion between the actuating arm 85 and the arm 79.

When the armature reaches a certain point in its upward movement under pull of the spring 65, the actuating arm 85 comes into engagement with the inner edge of the opening 86 of the contact arm 79, and on further upward movement of the armature the contact arm is moved inward until its contact 78 comes into engagement with the fixed contact 75, thereby closing the magnet circuit. The armature 67 is then drawn downward by the magnet and the actuating arm 85 swings outward. The actuating arm comes into engagement with the outer edge of the opening 86 of the contact arm 79 before the armature reaches the end of its downward movement, and continued outward movement of the actuating arm as the armature continues its downward movement then moves the contact arm outward to carry its contact 78 away from the fixed contact 75, thereby opening the magnet circuit to deenergize the magnet and release the armature so that the armature may again be moved gradually upward by the spring 65.

The contact arm 79 is extended upward above the contact 78 and has at its upper end a small plate, or armature, 87 which extends near one end 5 of the magnet pole 70. When the magnet is energized by the closing of its circuit between the contacts 75 and 78, the armature 87 is pulled inward by the magnet and the contact 78 is thereby held tightly against the contact 75 and all possibility of imperfect contact is thus avoided.

One end of the magnet coil is connected to the binding post 44 from which connection is made through the wire 43, terminal 42, and terminal button 33 to one terminal of the battery. The other end of the magnet coil is connected to a binding screw 88 through which connection is made to the bracket 76 which carries the fixed contact 75, and the circuit is completed from the movable contact 78 through 55 the contact arm 79, bracket 80, binding post 90, and wire 91 to a plate 92 which is in electrical connection with the walls of the container 20 from which connection is made back to the battery through the terminal button 35.

It is important that the mechanism for controlling the lamp circuit to cause the intermittent flashing of the lamp should be thoroughly protected from any access of moisture, water, or dirt. This mechanism is, therefore, mounted within the closed container 20, and the container is made water tight to guard against the entrance of any moisture or dirt. It is most desirably a cylindrical metal box as shown, having a flanged cover which fits down over the

open top of the body of the box and through which the lamp-supporting post 21 extends. When the controlling mechanism has been assembled within the box and connections made by the wires 45 and 46 to the lamp socket on the post 21, the cover is placed on the box and is most desirably sealed, as by means of solder, as indicated at 93 in Fig. 2. This not only insures against the entrance of moisture, but also provides a permanently closed until containing and protecting the parts of the complete apparatus which might be injured by careless or unskillful handling.

The post 21 is secured in a central opening 15 in the cover of the container in any suitable manner to insure a strong, water-tight joint, and the opening at the top of the post through which the wire 46 passes for connection to the outside of the lamp socket in the construction shown, is also sealed in a suitable manner to 20 prevent entrance of moisture. The lamp socket is secured to the top of the post by means of a screw 94, thereby insuring a tight joint at this point.

The container 20 is removably held in position against the under side of the cover 11 of the battery casing by means of spring clips 95 secured to the cover 11 and adapted to engage beneath a circumferential rib 96 on the side 30 of the container, the clips being formed with their lower ends turned outwardly so that the container may be attached to the casing cover 11 by simply entering the lamp-supported post 21 in the hole in the cover and pushing the container up against the under side of the cover. No angular positioning of the container with 35 respect to the cover about its vertical axis is required, and the cover may be readily removed by simply pulling it free from the spring 40 clips.

For securing the cover 11 to the body 10 of the battery casing, the body is provided with two undercut ears, or hooks, 97, which are secured at diametrically opposite points to the side of the body, and project above the top edge of the body, and the cover 11 is provided with two oppositely positioned ears, or keepers, 98, which extend outwardly from the upper surface of the cover to cooperate with the hooks 97 and have upwardly turned ends adapted to lie outside the upper ends of the hooks. The cover may thus easily and quickly be fastened securely to the body by placing it on the body with its flange extending down about the upper end of the side wall of the body and then turning it to enter its ears 98 beneath the undercut ends of the hooks 97. A padlock 99, having its bow passed through registering openings 100 in the flange of one of the ears 98 and the upper end of the coacting hook 97, serves 60 to securely hold and lock these parts together and thus prevent the cover 11 from becoming released by being accidentally or unauthorizedly turned relatively to the body 10.

Instead of using a Fresnel lens of the usual form open at both its upper and lower ends and depending on the cap 12 to make a top closure for the space within the lens, a lens having an integral top wall 105 is most desirably used. 70 This gives absolute insurance against the entrance of liquid or moisture at the top of the lens. And in order to further insure against any liquid passing from the space within the lens down through the opening 22 in the top 75

wall of the casing cover 11 through which the lamp-supporting post 21 passes, the edge of this opening 22 is at a level above the bottom edge of the lens, as clearly shown in Fig. 1. In 5 the construction shown, instead of having the top wall of the cover provided with an upwardly extending flange about the opening 22, the edge of the opening is raised above the bottom edge of the lens by having the central portion of the 10 top wall of the cover upwardly dished. This has the advantage of providing a downwardly sloping surface about the opening. With the edge of the opening 22 above the bottom edge of the lens, any small amount of water which 15 may collect in the bottom of the space within the lens, as from condensation of moisture within said space, is prevented from finding its way through the opening down into the container. With the bottom of the lens seated against a gasket 106, as shown, or other suitable packing, liquid cannot enter beneath the bottom 20 of the lens and the amount of liquid which will collect in the bottom of the lens chamber will be so small that there will be no danger 25 of the liquid level rising to the edge of the opening; and if the joint between the bottom of the lens and the cover wall is such as to permit the entrance of liquid, it would also permit liquid to escape from within the lens, and the 30 higher level of the central opening would in this case also serve as a guard against any liquid that might so enter passing through the opening 22 down into the container.

In assembling the parts of the apparatus, the 35 lens is secured to the cover 11, and a lamp-supporting and circuit-controlling unit, consisting of the closed container 20 with the circuit-controlling mechanism mounted therein and a lamp-supporting post 21 mounted thereon, is 40 placed in position against the under side of the top plate of the casing cover 11 held by the spring clips 95; and the battery cells are placed in the casing E on the supporting plate 25 connected in series by means of the connecting card 27. The 45 cover 11 is then placed and secured on the casing body 10. When the cover is placed on the casing body, the contact terminal 42 at the center of the bottom of the container 20 comes into engagement with the spring-supported contact button 50 33, and the spring-supported contact button 35 makes contact with the bottom of the container, both contact buttons being depressed sufficiently to insure good electrical contacts. The pressure of the contact buttons against the container also 55 aids in holding the container securely in position.

Because of the terminal buttons 33 and 35 making engagement, one with the contact 42 at the center of the bottom of the container and the 60 other making contact with the bottom of the container at a point spaced radially outward from the center, there is no need of having the container turned about its vertical axis to any particular position with relation to the battery or 65 to the battery casing, nor is there any necessity of having the battery oriented, or set in any particular angular relationship to the container. This makes for simplicity in construction and ease in assembling the parts.

70 And when the container is simply placed against the under side of the casing cover 11 and held by the spring clips, with the lamp-supporting post extending through the opening 22, the lamp, because of the top of the container being held 75 against the flat bearing surface of the under side

of the cover and the supporting post fitting in the opening 22, will necessarily be positioned both vertically and horizontally at the focal point of the lens, and no special care or adjustment to insure proper positioning of the lamp is required.

In order to renew the battery, it is necessary only to release and remove the casing cover 11 lift out the battery cells and replace them with new ones, and then replace the cover, and no care is required to insure any particular angular relationship between the battery and the container 20 to bring the contacts into register. To renew a lamp bulb, the cover 11 is removed, the casing 20 pulled away from the cover, and then replaced when a new bulb has been substituted. If the circuit-controlling mechanism requires attention or repair, the lamp and circuit-controlling unit may be removed and replaced with a new one.

While the particular apparatus shown is especially intended for use as a portable or hand lantern which may be carried around or conveniently placed in temporary locations, the device shown is, of course, equally applicable for permanent installation, the handle 16 being omitted if desired, when so used. Obviously, also, features of the invention may be embodied in apparatus other than self-contained apparatus in which the battery is contained within a casing forming part of the apparatus. It will be understood also that the invention is not to be limited to the exact construction and arrangement of parts shown, but that it includes changes and modifications thereof within the claims.

The electrically energized driving mechanism shown and described herein is claimed per se in Patent No. 1,878,076, dated September 20, 1932, granted on my application Serial No. 345,193. The circuit controlling mechanism shown and described herein is claimed per se in my application Serial No. 695,402, filed October 27, 1933, as a division of this application.

What I claim is:

1. A flashing lantern, comprising an electric lamp, an enclosure therefor, a battery casing having a removable top on which the lamp enclosure is mounted, a battery within the casing for supplying current to the lamp, a hermetically sealed container mounted within the battery casing, means for removably mounting said container, a lamp support extending from said container through an opening in the top of the battery casing, circuit connections between the battery and the lamp, and means for intermittently closing the lamp circuit, mounted with said container and connected in the lamp circuit between the battery and the lamp.

2. A flashing lantern, comprising a battery casing having a removable cover, a Fresnel lens mounted on the casing cover, a hermetically sealed container within the battery casing, means for removably securing said container to the under side of said casing cover, a lamp support mounted on said container and extending through an opening in said casing cover, an electric lamp on said lamp support positioned at the focus of the Fresnel lens, a battery within the battery casing, circuit connections between the battery and the lamp, and circuit-controlling means within said container connected in the lamp circuit between the battery and the lamp for intermittently closing the circuit to said lamp.

3. A flashing lantern, comprising a battery casing having a removable wall portion, a Fresnel

- lens mounted on the casing, a lamp-supporting and circuit-controlling unit comprising a closed container and a lamp support extending from the container and circuit-controlling mechanism 5 within the container for intermittently closing the lamp circuit momentarily, circuit connections for providing a lamp circuit between a battery within the battery casing and a lamp on the support, and means for removably securing said unit 10 within the battery casing with the lamp support extending through an opening in the wall of the casing in position to support an electric lamp at the focus of the Fresnel lens.
4. A flashing lantern, comprising a Fresnel lens, 15 a wall on which the lens is mounted, a lamp-supporting and circuit-controlling unit comprising a closed container and a lamp support extending from the top of the container and provided with a lamp socket and circuit-controlling mechanism 20 within the container and circuit connections between the controlling mechanism and the lamp socket, and holding means extending from said wall for engaging and removably holding the container beneath said wall, said wall having an 25 opening concentric with the vertical axis of the lens and being formed to provide a seat for the top of the container, whereby when the container is placed against the wall with its lamp support passing through said opening the lamp support 30 will be positioned to support a lamp at the focus of the lens.
5. A flashing lantern, comprising a battery casing having a removable wall portion, a Fresnel lens mounted on the casing, a lamp-supporting and 35 circuit-controlling unit within the casing comprising a closed container and a lamp support extending from the container and provided with a lamp socket and circuit-controlling mechanism within the container connected in the lamp circuit for intermittently closing the lamp circuit momentarily, means for removably mounting said unit within the battery casing with its lamp support extending through an opening in the casing wall to support a lamp within said lamp enclosure, circuit controlling means connected in the lamp 40 circuit for intermittently closing the lamp circuit mounted within said container, and circuit connections providing a lamp circuit between the battery and a lamp on the lamp support.
6. A flashing lantern, comprising a battery casing, a lamp enclosure mounted on said casing, a lamp support extending upward through an opening in the top wall of the casing within the lamp enclosure and removable from below said top wall, means for removably securing said lamp support to said top wall, and circuit connections for providing a lamp circuit between a battery within the battery casing and a lamp on the lamp support, the edge of said opening in said top wall being 45 above the bottom of the lamp enclosure.

battery casing and having a central terminal to make contact with the central contact terminal of said container and a terminal spaced laterally from the central terminal to make contact with the bottom of the container, whereby proper connections will be established between the battery and the lamp circuit when the container is in place, irrespective of the relative angular positions of the container and the battery.

7. A flashing lantern, comprising a battery casing having a removable wall portion, a lens mounted on the casing, a lamp-supporting and circuit-controlling unit comprising a closed container and a lamp support extending from the container and circuit-controlling mechanism 15 within the container connected in the lamp circuit for intermittently closing the lamp circuit momentarily, means for removably securing said unit within the battery casing with the lamp support extending through an opening in the 20 wall of the casing in position to support an electric lamp at the focus of the lens, and circuit connections for providing a lamp circuit between a battery within the battery casing and a lamp on the lamp support.

8. A flashing lantern, comprising a battery casing having a removable wall portion, a lamp enclosure mounted on said casing, a battery within the casing for supplying current to the lamp, a container having a lamp support mounted thereon, means for removably mounting the container within the battery casing with its lamp support extending through an opening in the casing wall to support a lamp within said lamp enclosure, circuit controlling means connected in the lamp 30 circuit for intermittently closing the lamp circuit mounted within said container, and circuit connections providing a lamp circuit between the battery and a lamp on the lamp support.

CHARLES F. WALLACE.
